John O. Van Koert, West Newbury, Mass., assignor to Towle Manufacturing Company, Newburyport, Mass., a corporation of Massachusetts

Application December 12, 1951, Serial No. 17,691

Term of patent 14 years

(Cl. D54—12)

To all whom it may concern:

Be it known that I, John Owen Van Koert, a citizen of the United States of America, residing at 743 Main Street, in West Newbury, county of Essex, and Commonwealth of Massachusetts, have invented a new, original, and ornamental Design for a Fork or Similar Article, of which the following is a specification, reference being had to the accompanying drawings, forming a part thereof.

Fig. 1 is a front elevational view of a fork, showing the essential features of my new design in full lines, the back of a handle being substantially plain;

Figs. 2, 3 and 4 are sections taken on the lines 2—2, 3—3 and 4—4 respectively of Fig. 1; and

Fig. 5 is a side elevational view of the disclosure in Fig. 1.

The drawing shows my design as embodied in a fork, but it is understood that the same may be applied to other articles of flatware without departing from the spirit of the invention.

I claim:

The ornamental design for a fork or similar article, as shown and described.
